ROBERT F. MINTY, OF MONTREAL, QUEBEC, CANADA.

HAIR WAVER.

Application filed February 16, 1924, Serial No. 693,339, and in Canada July 5, 1923.

This invention relates to new and useful improvements in hair curlers or wavers and the object of the invention is to provide a hair curler which will produce a permanent curl or wave.

Another object is to provide a safe device in which the hair may be boiled without injuring the scalp.

A further object is to provide a hair curler or waver in which the hair is prevented from burning when being heated.

In my invention I provide a tube which is placed within a heating element. The tube is fitted with a cap at one end and a flexible rubber tube at the other. The hair is coiled and placed within the tubes from the rubber end and clamped by a special clamping device to make it water tight. Water is then poured into the tubes and a cap is placed or screwed to the end of the tubes. The water is raised in temperature by the heating element surrounding the tubes and the hair is boiled to produce a permanent curl or wave in the hair.

In the drawings:

Figure 1 is a longitudinal sectional elevation of the device.

Figure 2 is a cross sectional elevation taken on the line 2-2 Figure 1.

Figure 3 is a plan view of the apparatus.

Figure 4 is a perspective view of the clamp detached from the tube.

Referring more particularly to the drawings, 11 designates a metal tube which is provided with a screw cap 12 at one end and a rubber tube 13 at the other end. A hinged clamp is provided to close the end of the rubber tube to make it water tight. The clamp is made of two sides, 14 and 15 which swivel about the pin 16. It is also provided with a swivel bolt 17 mounted on

a pivot pin 18 which is placed through one of the sides 14. A slot 19 is cut in the side 15 and is adapted to receive the eyebolt. A knurled nut is screwed on to the eyebolt and adapted to engage with the side 15 thus clamping the sides 14 and 15 together. The hair 20 is coiled around a cone or the like and is placed into the tubes from the rubber tube end. An electrical heating element 21 is provided to pass around the tube 11 and is connected to a power circuit by means of socket 22 and the cable 23.

The operation of the device is as follows: The hair is curled or wound around a cone 55 and placed into the tubes and the clamp is placed over the rubber to make it water-tight. The heating element is positioned around the metal tube which is then filled or partly filled with water and closed with 60 the cap 12. The current is allowed to flow into the heating element which in turn heats the tube and the water contained therein until the water boils and thus boils the hair contained therein. By this method the curl, 65 or wave, put in the hair before insertion into the tube becomes permanent.

Having thus described my invention, what I claim is;—

A hair waving device comprising a metal 70 tube having an imperforate closure at one end and being open at the other end, a cone insertable in said tube and about which the hair is adapted to be wound, a flexible tube secured to the open end of the metal tube, 75 and provided with means for clamping it about the hair and means for heating said tube.

In witness whereof, I have hereunto set my hand.

ROBERT F. MINTY.
